UNITED STATES PATENT OFFICE.

OWEN C. FROM, OF NEW YORK, N. Y., ASSIGNOR TO WESTERN ELECTRIC COMPANY,
INCORPORATED, OF NEW YORK, N. Y., A CORPORATION OF NEW YORK.

REGISTERING MECHANISM.

Application filed October 18, 1923. Serial No. 669,252.

To all whom it may concern:

Be it known that I, OWEN C. FROM, a citizen of the United States of America, residing at New York, in the county of New York, State of New York, have invented certain new and useful Improvements in Registering Mechanisms, of which the following is a full, clear, concise, and exact description.

10 This invention relates to telephone exchange systems, and more particularly, to recording and registering mechanisms for use therein.

In telephone systems of the automatic and semi-automatic types, it is found desirable to register on apparatus located at the central office the designations of wanted lines or circuits. A designation thus registered may later be used for governing the selective operations of switches to extend the required connection or for controlling well-known indicating mechanism.

The object of the invention is to provide a unitary registering mechanism of simple construction and efficient in operation for registering all digits of called designations.

A feature of the invention relates to the provision of a registering mechanism of the coordinate switch type, the vertical bars of which are operated in different combinations in response to each series of impulses and the horizontal bars of which are operated in succession in response to a progressive series of impulses to operate registering elements for recording the digit values of the several digits of call designations.

40 A further feature of the invention relates to the provision in a unitary registering mechanism of a group of registering elements for each series of impulses to be registered and of means for operating said elements in various combinations to translate digit values of a decimal character into registrations of a non-decimal or code character.

This and other features of the invention will be more clearly apparent from a consideration of the following description taken in connection with the accompanying drawings and the appended claims.

45 Referring to the drawings, Figs. 1 and 2, taken in conjunction with each other, with Fig. 2 at the right of Fig. 1, illustrate so

much of a telephone exchange system incorporating a receiving, recording and registering mechanism of a type embodying the present invention as is necessary for a complete understanding thereof. Fig. 1 discloses a subscriber's line terminating in a switch at the central office, other switches for extending the line, together with details of an impulse receiving and recording mechanism responsive to designation impulses for establishing the record thereof at the central office.

Fig. 2 shows a unitary registering mechanism of the coordinate type comprising eight groups of registering elements corresponding to eight digits of a called designation, the four vertical bar magnets in the lower portion of the figure, the eight horizontal bar magnets at the immediate left of the several groups of registering elements and a chain of progression relays on the left of the horizontal magnets.

While applicant's invention has for convenience been applied to a particular type of automatic telephone system such as disclosed, for example, in the patent to S. B. Williams, Jr. No. 1,517,831, issued Dec. 2, 1924, it is to be understood that it is equally applicable to other types of systems.

In the system disclosed the subscriber's line 100 extends to the central office and there terminates in a line switch 102 diagrammatically shown. The line switch 102 is adapted to extend the subscriber's line 100 to any of a number of trunks, one of which 104, 105 is illustrated extending to a first selector switch 106. Such switch 106 may be of the same character as the line switch 102 and serves to extend the incoming trunk 104, 105 to other trunks such as 142, 143 and 144. Obviously trunks 142, 143 and 144 may lead to succeeding selective devices where they may be selectively connected to other trunks and so on until the desired connection is completed.

Also located at the central office is an impulse receiving and recording mechanism comprising an organization of relays and circuits, the function of which is to receive a series of impulses generated through the operation of the dial of the calling subscriber's line and to record the designations represented by such impulses. There may be any desired number of these recording

mechanisms arranged to serve a group of subscribers' lines, the particular one to be taken for use at any particular time depending upon its busy or idle condition. A 5 selecting switch 103 is provided for associating an idle one of the recording mechanisms comprising the remainder of Figs. 1 and 2, with the particular trunk 104, 105 to which the calling subscriber's line 10 has been extended by the switch 102.

The switches 102, 103 and 106 may be of the general type shown and described in detail in the patent to C. L. Goodrum, No. 1,551,024, issued August 25, 1925, or of any 15 well-known type such as power driven selectors, or switches in which multi-contact relays are employed for building up the connections with means for selecting and operating the necessary relays. While the recording and registering mechanism embodying the invention is particularly adapted for use in systems employing switches of the character illustrated, it is to be understood that any other suitable form of 20 switching device may be used instead.

The registering mechanism shown in Fig. 2 may also be of the same general type and operate in a similar manner to the switching device, described in the hereinbefore mentioned patent to C. L. Goodrum.

Having described the apparatus to be employed and the general mode of its operation, a detailed description will now be given of the operation of the system. It 35 will be assumed that the calling subscriber 100 desires to obtain connection with a line whose office and numerical designation is BIN 1035-W, and to initiate a call, removes his receiver from the switchhook. When the receiver is thus removed, the line 40 switch 102 operates to extend the calling line to an idle trunk 104, 105. Moreover, the selecting switch 103 operates to associate the idle recording mechanism shown in detail with the selected trunk 104, 105. In 45 response to these operations a circuit is closed from battery through resistance 112, right winding of impulse relay 111, through the switch 103, conductor 105, through the switch 102, over the loop of the calling line 100 and returning through the switch 102, conductor 104, through the switch 103, left winding of the balancing coil 113 to ground. Relay 111 operates and 50 closes a circuit from ground through its armature and front contact, winding of slow-to-release relay 115 to battery causing the operation of relay 115.

60 Relay 111, in operating, also closes a circuit in parallel with relay 115 through the left winding of relay 119. Relay 119 operates and closes a circuit from battery, resistance 120, left back contact of relay 118, right contact of relay 119, conductor 116, outer left back contact of relay 117 to

ground through both windings of relay 125. The current flowing in this circuit causes the windings of relay 125 to aid one another, whereupon relay 125 operates and closes a locking circuit for itself. This locking 70 circuit may be traced from ground through the right winding and inner right contact of relay 125, conductor 133, right back contact of relay 114, resistance 120 to battery. As soon as the relay 125 attracts its 75 armatures a circuit is closed from battery, left winding of relay 119, inner left contact of relay 119, outer right back contact of relay 121 and outer left back contact of relay 122, in parallel, outer right back 80 contact of relay 122, outer right back contact of relay 123, outer right back contact of relay 124, outer left front contact of relay 125, windings of relay 121 in series to ground. This circuit is not effective to energize relay 121 at this time due to the direct connection in shunt of the windings of relay 121 to ground at the front contact of relay 111. Nothing further occurs until the calling subscriber manipulates his dial 85 in response to the dialing tone which is inductively transmitted over the dialing circuit above traced from the right winding of balancing coil 113.

When the subscriber operates his dial 101 90 to send the impulses corresponding to the first code letter B of the office designation of the wanted line, the letter having a digit value of 2, the circuit of relay 111 is opened twice causing relay 111 to deenergize and 100 energize twice in succession. When relay 111 deenergizes it opens the circuits of relays 119 and 115. Relay 115 being slow-to-release maintains its armatures attracted during the interruptions of its circuit. When, therefore, relay 111 closes its back contact, a circuit is closed from ground, back contact of relay 111, right contact of relay 115, winding of relay 118 to battery. Relay 118 operates and at its left armature 105 opens the initial energizing circuit above traced for relay 125. At its right armature relay 118 closes a circuit from ground, right front contact of relay 118, inner left contact of relay 114 to battery through the winding of relay 117. Relay 117 energizes and closes a locking circuit for itself from battery through its winding, inner left contact of relay 114 to ground, at the inner left front contact of relay 117. At its outer left armature relay 117 also opens the initial energizing circuit of relay 125 at another point.

Meanwhile, relay 119 whose original energizing circuit was opened when relay 111 115 retracted its armature is maintained energized over the circuit previously traced for relay 121. The shunt around this relay having now been removed, relay 121 attracts its armatures closing a locking cir- 120 130

cuit for itself through its right winding and inner right front contact to battery on conductor 133. This circuit shunts the original energizing circuit through relay 119 and 5 relay 119 thereupon deenergizes. At its outer left contact relay 119 connects ground to the circuit of relay 118 supplementing the ground from the back contact of relay 111, thus shortening the open circuit period 10 over which relay 118 must hold its armatures attracted.

Relay 121 also closes a circuit from ground, right winding of relay 119, inner left contact of relay 121, left winding of 15 relay 125, inner right front contact of relay 125, conductor 133, left back contact of relay 114, resistance 120 to battery. The current in this circuit flows in the opposite direction to the original energizing current 20 flowing through the left winding. The windings of relays 125, as well as those of the other counting relays, are so wound that these opposing currents neutralize one another and relay 125 retracts its armatures. 25 The other counting relays operate in a similar manner, that is, they operate through their two windings in series, lock through one winding and release due to differential current through their two windings. The 30 current in the above traced releasing circuit has a differential effect upon the left winding of relay 119 causing that relay to release more quickly than it otherwise would. The magnetic effect of the right winding is not sufficient to reenergize the 35 relay nor materially hinder its energization when the left winding again becomes effective. When relay 111 attracts its armature at the end of the first interruption of its 40 circuit, the energizing circuit for relay 119 is again closed and this relay operates. A circuit is now closed from grounded battery, left winding of relay 119, inner left front contact of relay 119, outer right front contact of relay 121 and in parallel through the 45 outer right and left back contact of relay 122, thence through the outer right back contact of relay 123, outer right back contact of relay 124, outer left back contact of 50 relay 125, through the two windings of relay 122 to ground. Relay 122 is shunted by direct ground at the armature and front contact of relay 111 at this time and does not attract its armatures.

55 When relay 111 retracts its armature in response to the second and last interruption of its circuit by the dial 101, the shunt around relay 122 is removed and that relay attracts its armatures. At its inner right front contact relay 122 establishes a locking circuit from ground through its right winding to battery over conductor 133, this circuit shunting relay 119 and that relay retracting its armatures.

60 Relay 122 also closes a circuit through the

right winding of relay 119, inner left front contact of relay 122, left winding of relay 121, inner right armature of relay 121 to battery over conductor 133. This circuit places the windings of relay 121 in opposition so that relay 121 thereupon releases. 70

At the close of the second opening of the circuit of relay 111 that relay again operates causing, in turn, the operation of relay 119 and the closure of a circuit for relay 123 75 which circuit is ineffective due to the shunt closed at the front contact of relay 111. It is to be noted in connection with the foregoing description of the operation of relays 117 and 125 that relay 125 releases prior 80 to the operation of relay 117 so that the circuit which would otherwise exist for operating relay 126 is not at this time effective.

The circuit of relay 111 is maintained for a comparatively long time between the sending of the first and second digit series of impulses and relay 119 being energized 85 ground is removed from the circuit of relay 118 long enough to permit that relay to retract its armatures. Relay 118 on deenergizing closes a circuit from ground at its right back contact, outer left contact of relay 114, inner right contact of relay 117, back contact of relay 148, left back contact 90 of relay 126, outer left back contact of relay 124, outer left back contact of relay 121, conductor 137, vertical bar magnet 202 to battery. Magnet 202 attracts its armature, rotates the vertical bar of the registering mechanism associated therewith, and establishes a circuit from ground at its armature contact over conductor 205, inner right back contact of transfer relay 207 to battery through the winding of horizontal bar magnet 206. Magnet 206 energizes in this 95 circuit closing a locking circuit for itself extending through its winding and the winding of relay 207 in series, the outer front contact of magnet 206, conductor 145 to ground at the left contact of relay 115. Relay 207 being shunted by direct ground at the armature contact of magnet 202 does not energize at this time. Magnet 206, upon 100 energizing, also rotates the horizontal bar associated therewith, which in conjunction with the operated vertical bar operates the card 222 located at the junction of the two operated bars, in the well-known manner.

With counting relay 122 energized a circuit is also closed which may be traced from ground at the front contact of relay 111, inner left front contact of relay 119, left front contact of relay 122, conductor 147, inner normal contacts of the preliminary pulse relay 200, winding of relay 200, conductor 145 to ground at the left contact of relay 115. Relay 200 energizes and locks over the alternate contact of its inner left armature, conductor 134, resistance 120 to battery. This relay remains locked until 110 115 120 125 130

the sender is dismissed and at its outer left front contact joins conductor 138 to the conductor 223 leading to the vertical magnet 201.

5 In this connection it is to be noted that the vertical magnet 201 is not operable until after at least two impulses have been recorded on the counting relays. For example, if a single impulse is recorded in the 10 first digit series, then at the end of the series only the counting relay 121 remains energized and since the counting relay 122 has not energized, the circuit previously traced for relay 200 has not been completed. 15 Therefore, when relay 118 deenergizes upon the termination of the single impulse, the circuit previously traced from ground at the right back contact of relay 118 to the outer left armature of relay 121 extends over the 20 front contact of this armature, conductor 138, the outer back contact of relay 200, conductor 135 to battery through the winding of relay 114. Relay 114, thereupon, energizes opening the holding circuits of counting relay 121 and relay 117. These relays 25 thereupon release. Thus, if only a single impulse is received in the first digit series, no magnets of the registering mechanism are operated. The circuits are designed to 30 function in this manner in order that a false registration may not result from an initial preliminary impulse resulting from conditions existing on the line when it is cut through to the recording circuits, or resulting 35 from the accidental operation of the switchhook at the substation.

As soon as magnet 206 operates following the recording of the first code letter, a circuit is also closed from battery, winding of 40 relay 114, conductor 135, left back contact of transfer relay 207, inner front contact of magnet 206, conductor 145 to ground at the left contact of relay 115. Relay 114 energizes opening the holding circuit of relay 45 117, and at its right back contact opens the locking circuit of counting relay 122. As soon as the relay 117 deenergizes the circuit previously traced for magnet 202 is opened permitting the restoration of the operated 50 vertical bar. With magnet 202 deenergized the shunt around the winding of transfer relay 207 is removed and relay 207 energizes in the holding circuit of magnet 206. Relay 207, upon energizing, opens the circuit of 55 relay 114 which thereupon releases. The operated card 222 is now held operated by the horizontal bar which was operated by magnet 206. The recording and registering circuits are now in condition for the receipt 60 of the second series of impulses.

As it has been assumed that the second code letter is I having a numerical equivalent of 4, the subscriber now manipulates his dial 101 to cause four circuit interruptions 65 of his line circuit. With relays 118, 117 and

114 deenergized and relays 111 and 119 energized, the above traced circuits for operating relay 125 and preparing relay 121 for operation are completed. In response to the first interruption caused by the dial 101, 70 relay 111 releases its armatures and relays 118, 117 and 121 operate. Relay 121 locks and closes the differential circuit for releasing relay 125. In response to the second interruption, relay 122 operates and causes 75 the differential release of relay 121 as before described. In response to the third interruption relay 123 is operated over a circuit extending from battery, left winding and inner left contact of relay 119, outer right back contact of relay 121, outer right front contact of relay 122 to ground through both windings of relay 123. Relay 123 energizes and locks from ground through its right winding and inner right contact to battery 80 on conductor 133, thereby causing the differential release of relay 122. In response to the fourth interruption, relay 124 is operated over a circuit extending from battery, left winding and inner left contact of relay 85 119, outer right back contact of relay 121, outer right back contact of relay 122, outer right front contact of relay 123 to ground through both windings of relay 124. Relay 124 thereupon energizes and locks through 90 its right winding and inner right contact to battery on conductor 133, thereby causing the differential release of relay 123.

Relay 117 having operated following the energization of relays 118 and 125, when, 100 therefore, the second digit series of interruptions ceases and relay 118 deenergizes, with counting relay 124 operated and the remaining counting relays deenergized, a circuit is closed from ground at the right 105 back contact of relay 118, the outer left back contact of relay 114, the inner right front contact of relay 117, the back contact of relay 148, the left back contact of relay 126, the outer left front contact of relay 124, 110 conductor 139 to battery through the vertical magnet 203 of the registering mechanism. Magnet 203 operates the vertical bar associated therewith and at its armature contact connects ground to conductor 205. 115 A circuit is now established for the horizontal bar magnet 208 extending from ground on conductor 205, the inner right armature and front contact of relay 207, the inner right back contact of relay 209 to battery 120 through the winding of horizontal magnet 208. Magnet 208 thereupon energizes locking itself in series with transfer relay 209 over a circuit extending from battery, winding of magnet 208, winding of relay 209, outer 125 front contact of magnet 208 to ground at the outer right contact of relay 207. Relay 209 does not, however, operate in this locking circuit since it is shunted at the contact of magnet 203. Magnet 208, upon energizing, 130

- ing, rotates the horizontal bar associated therewith, which in conjunction with the vertical bar operated by magnet 203 operates the registering card 224 located at the junction of these two bars. In addition magnet 208 at its outer contact closes a circuit for relay 114 extending from battery, winding of relay 114, conductor 135, left front contact of relay 207, left back contact of relay 209, armature and contact of magnet 208 to ground at the outer right front contact of relay 207. Relay 114 energizes and functions as before to release relay 117 and the operated counting relay 124. As soon as relay 117 deenergizes the operating circuit of magnet 203 is opened thereby releasing the operated vertical bar. The release of magnet 203 also removes the shunt from the winding of transfer relay 209 which thereupon energizes in the locking circuit of magnet 208 opening at its left back contact the circuit of relay 114. The operated card 224 is now held operated by the bar which was operated by magnet 208.
- 25 The recording and registering circuits are now in condition to receive the third series of impulses.
- The subscriber next operates his dial 101 to interrupt the circuit of relay 111 six times in accordance with the third code letter which was assumed to be M. At the end of the fourth circuit interruption relays 118, 117, and the counting relay 124 are all in an energized condition as described in connection with the preceding digit series and an energizing circuit is prepared through the operation of relay 124 for the counting relay 125. Upon the fifth interruption relay 125 energizes over a circuit from battery through the left winding and inner left armature contact of relay 119, the outer right back contact of relays 121, 122 and 123, the outer right front contact of relay 124 to ground through both windings of relay 125.
- 40 Relay 125 thereupon locks from ground through its inner right front contact to battery on conductor 133 and closes a circuit through the left winding of relay 124 for causing it to be differentially released. Relay 125 at its outer right contact also closes a circuit from ground at the outer right contact of relay 117, outer right contact of relay 125, right back contact of relay 127 to battery through the winding of relay 126.
- 45 Relay 126 energizes and closes a locking circuit for itself extending through its winding and the winding of relay 127, the right contact of relay 126 to ground at the outer right contact of relay 117. Relay 127 however, does not energize in the locking circuit of relay 126 since it is shunted by direct ground connected through the outer right contact of relay 125.
- 50 In response to the sixth and last interruption of the circuit of relay 111, a circuit is established from battery left winding and inner left contact of relay 119, outer right back contact of relays 121, 122, 123 and 124, outer left front contact of relay 125 to ground through the windings of relay 121 in series. Relay 121 thereupon energizes and locks from ground over its right winding and inner right contact to battery on conductor 133 and at its inner left front contact closes the previously traced circuit through the left winding of relay 125 causing relay 125 to be differentially released. As soon as relay 125 deenergizes the shunt around relay 127 is opened whereupon relay 127 energizes in the holding circuit of relay 126.
- 55 At the termination of the sixth and last impulse of the third series, relay 118 releases and with relay 121 energized and the remaining counting relays deenergized, a circuit is closed from ground at the right back contact of relay 118, the outer left back contact of relay 114, the inner right contact of relay 117, the back contact of relay 148, the left front contact of relay 126, the inner left front contact of relay 127, the outer left back contact of relay 124, the outer left front contact of relay 121, conductor 138, the outer left front contact of relay 200, conductor 223 to battery through the winding of vertical magnet 201. A second circuit is also closed from ground at the back contact of relay 118, over the circuit traced to the inner left front contact of relay 127, outer left front contact of relay 127, conductor 140, magnet 204 to battery. These magnets 201 and 204, upon energizing, operate the vertical bars associated therewith and at their armature contacts connect ground to the conductor 205 for the purpose of energizing the horizontal magnet 210. The circuit of magnet 210 extends from conductor 205, through the inner right front contacts of relays 207 and 209 and the inner right back contact of relay 211 to battery through the winding of magnet 210. Magnet 210, upon operating, rotates the associated horizontal bar and locks itself through the winding of transfer relay 211. Magnet 210 also causes the operation of relay 114 as previously described, which in turn, releases relays 117, 121, 126 and 127. As soon as relay 117 releases, the operating circuits of magnets 201 and 204 are opened and these magnets permit the restoration of the operated vertical bars. With these magnets deenergized the transfer relay 211 operates in the holding circuit of magnet 210 opening the circuit of relay 114. Through the joint operation of the operated vertical and horizontal bars the registering cards 225 and 226 are operated and are maintained operated solely through the operation of magnet 210 after the release of magnets 201 and 204. The recording and registering

circuits are now in condition to receive and register the fourth or thousands series of impulses.

The subscriber next operates his dial 101 5 to interrupt the circuit of relay 111 once, the thousands digit being assumed to be 1. At the end of the first circuit interruption, relays 117, 118 and 121 are in an energized condition as described in connection with the 10 preceding digit series. Since only a single circuit interruption results from dialing the thousands digit 1, the relay 111 remains energized following this interruption and relay 118 deenergizes, closing a circuit extending 15 from ground at its right back contact, outer left back contact of relay 114, inner right contact of relay 117, back contact of relay 148, left back contact of relay 126, outer left back contact of relay 124, outer left 20 front contact of relay 121, conductor 138, outer front contact of relay 200, conductor 223 to battery through the winding of vertical magnet 201. Magnet 201 operates the 25 vertical bar associated therewith and at its armature contact closes a circuit over conductor 205, the inner right front contacts of relays 207, 209 and 211, the inner right back contact of relay 213 to battery, through the horizontal magnet 212. Magnet 212 there- 30 upon rotates the horizontal bar associated therewith, locks itself through the winding of relay 213 and closes the circuit of relay 114. Relay 114, upon energizing, opens the 35 circuits of relays 117 and 121, whereupon magnet 201 is released. Through the con- 40 joint operation of the magnets 201 and 212, the registering card 227 is operated, this card being held operated through the continued operation of magnet 212 following 45 the release of magnet 201. As soon as mag- net 201 releases, the shunt around transfer relay 213 is opened and this relay energizes in the holding circuit of magnet 212, opening the circuit of relay 114. The recording 50 and registering circuits are now in a condition to receive and register the fifth or hundreds series of impulses.

The subscriber now manipulates his dial 101 to interrupt the circuit of relay 111 ten 55 times to record the hundreds digit 0. At the end of the sixth interruption relays 117, 118, 121, 126 and 127 are in an energized condition as described in connection with the third digit series. In a similar manner 60 in response to the seventh, eighth, ninth and tenth circuit interruptions, relays 122, 123, 124 and 125 energize in succession each in turn causing the deenergization of the counting relay preceding it. Thus at the 65 end of the tenth interruption relay 125 remains energized and locks, while the remaining counting relays are all deenergized. As soon as relay 125 energizes it establishes a circuit for relay 148 extending from battery through the winding of relay 148, right

front contact of relay 127, outer right contact of relay 125 to ground at the outer right contact of relay 117. When relay 111 remains energized at the end of the digit series and relay 118 deenergizes, no circuits 70 are established for vertical magnets of the registering mechanism, but a circuit is established from ground at the right back contact of relay 118, outer left back contact of relay 114, inner right contact of relay 117, front contact of relay 148, conductor 141, inner right front contact of transfer relays 207-213, inner right back contact of relay 215 to battery through the winding of magnet 214. Magnet 214 operates locking itself in series with the transfer relay 215 and closing the circuit of relay 114. Since no vertical bars have been operated, the operation of the bar associated with magnet 214 is without effect on the registering cards associated therewith. Following the energization of relay 114, relays 117, 126, 127, 148 and 125 deenergize. As soon as relay 148 deenergizes the shunt which has existed around the winding of transfer relay 215 is opened and relay 215 energizes in the holding circuit of magnet 214, in turn, opening the circuit of relay 114. The recording and registering circuits are now in a condition to receive and register the sixth or tens 95 series of impulses.

The subscriber now operates his dial 101 to interrupt the circuit of relay 111, three times to record the tens digit 3. At the end of the third interruption, relays 117, 118 and 123 are in an energized condition as previously described and when relay 111 remains energized at the termination of the digit series and relay 118 deenergizes, circuits are established for vertical magnets 201 and 202. The circuit of magnet 201 may be traced from ground at the right back contact of relay 118, thence as previously traced through the outer left back contact of relay 124, the outer left front contact of relay 123, conductor 138, the outer left front contact of relay 200, conductor 223 to battery through the vertical magnet 201. The circuit of magnet 202 may be traced from the outer left back contact of relay 124, the outer left back contact of relay 121, conductor 137, to battery through the vertical magnet 202. Magnets 201 and 202, upon energizing, cause the operation of the vertical bars associated therewith and establish a circuit over conductor 205 for the horizontal magnet 216 in a manner hereinbefore described in connection with the operation of other horizontal magnets. Magnet 216, upon operating, locks itself through the winding of transfer relay 217, rotates the horizontal bar associated therewith and establishes a circuit for the relay 114. Relay 114, upon energizing, releases 115 relays 117 and 123, whereupon the operated 120 125 130

vertical magnets 201 and 202 are released, releasing the operated vertical bars and permitting the energization of transfer relay 217. Through the conjoint operation of the 5 vertical and horizontal bars, the cards 228 and 229 are operated, these cards being maintained operated following the release of the vertical bars, through the continued operation of the horizontal magnet 216.

10 With relay 219 operated the circuit of relay 114 is opened and relay 114 deenergizes. The recording and registering circuits are now in condition to receive the seventh or units series of impulses.

15 The subscriber now operates his dial 101 to interrupt the circuit of relay 111 five times to record the units digit 5. At the end of the fifth interruption, relays 117, 118 and 125 are in an energized condition as hereinbefore described. Upon the termination of the fifth and last impulse, with relay 125 energized, a circuit is established from ground at the outer right contact of relay 117, the outer right contact of relay 125, 25 the right back contact of relay 127 to battery through the winding of relay 126. Relay 126 energizes, locking itself through the winding of relay 127 and its own right contact to ground at the outer right contact of relay 117. Relay 127 does not, however, energize in this locking circuit so long as relay 125 remains energized. When relay 111 remains energized at the termination of the series of impulses and relay 118 deenergizes, a circuit is established extending 30 from the right back contact of relay 118, thence as previously traced to the left armature and front contact of relay 126, the inner left back contact of relay 127, conductor 35 140 to battery through the winding of vertical magnet 204. Magnet 204, upon energizing, operates the vertical bar associated therewith and establishes a circuit over conductor 205 for the horizontal magnet 218 in 40 the manner previously described in connection with circuits of other horizontal magnets. Magnets 218, upon energizing, operates the associated horizontal bar, which in conjunction with the operated vertical 45 bar, causes the operation of the registering card 230. In addition magnet 218 locks itself through the winding of transfer relay 219 and closes a circuit for energizing relay 114. Relay 114, upon energizing, opens the 50 holding circuits of relays 117, 125 and 126, whereupon these relays release, relay 117, in turn, opening the energizing circuit of vertical magnet 204. Magnet 204, upon deenergizing, permits the restoration of the operated vertical bar and permits the energization of the transfer relay 219, which upon operating, opens the circuit of relay 114. The recording and registering circuits are now in condition to receive and register 55 the last or stations series of impulses.

The subscriber now manipulates his dial 101 to interrupt the circuit of relay 111 nine times to record the stations letter W. At the end of the ninth interruption, relays 117, 118, 124, 126 and 127 are in an energized 70 condition as previously described, and when relay 111 remains energized at the termination of the digit series and relay 118 deenergizes, circuits are established for the vertical magnets 203 and 204. The circuit 75 for magnet 203 may be traced from ground at the right armature and back contact of relay 118, thence as previously traced through the left front contact of relay 126, inner left front contact of relay 127, the 80 outer left front contact of relay 124, conductor 139, thence to battery through the winding of magnet 203. The circuit for magnet 204 may be traced from the inner left armature and front contact of relay 127, through the outer left front contact of relay 127, conductor 140, and thence to battery through the winding of magnet 204. Magnets 203 and 204, upon energizing cause the operation 85 of the associated vertical bars and also the operation of horizontal magnet 220 in a manner hereinbefore described in connection with the operation of other horizontal magnets. Magnet 220, upon energizing, operates the associated horizontal bar, locks it 90 self in series with transfer relay 221 and establishes the previously traced circuit for relay 114. Relay 114, upon energizing, opens the circuits of relays 117, 126, 127 and 124. Relay 117, upon deenergizing, opens 95 the previously traced circuits of magnets 203 and 204. As soon as magnets 203 and 204 deenergize, the operated vertical bars are released and the transfer relay 221 energizes opening the circuit of relay 114. 100 The conjoint operation of the operated vertical and horizontal bars causes the operation of registering cards 231 and 232, which cards are maintained in their operated condition by the magnet 220, following the deenergization of magnets 203 and 204. The entire office and numerical designations of the wanted line number have now been registered upon the registering mechanism. 105

In the foregoing description, the registration of all digits except digits 7 and 8 have been described. When the digit 7 is dialed, upon the termination of the circuit interruptions, relays 117, 126, 127 and 122 are in an energized condition and, therefore, conductors 137 and 140 are grounded to operate the vertical magnets 202 and 204, thus operating the second and fourth registering cards of the horizontal row of cards corresponding to the digit series being dialed. 110 When the digit 8 is dialed upon the termination of the circuit interruptions relays 117, 126, 127 and 123 are in an energized condition and therefore conductors 137, 138 and 140 are grounded to operate the vertical 115 120 125 130

magnets 201, 202 and 204, thus operating the first second and fourth cards of the horizontal row corresponding to the digit series being dialed.

- 5 Upon the completion of the registration of the entire office and numerical designations of the wanted line, a district marker is associated with the upper three groups of registering elements of the registering 70 mechanism and a line marker with the five lower groups of registering elements over the groups of conductors extending to the right margin of the figure, if the call is of a full mechanical class. If the call is of a 75 10 class in which connection must be established to the wanted line through a call indicator position of a manual office, all of the groups of registering elements are connected with the relay call indicator impulser of the 80 15 sender over the groups of conductors extending from the left of the several groups of registering elements. The district line markers and the call indicator impulser (not disclosed) may be associated with the 85 20 registering mechanism in the manner set forth in the aforementioned patent to S. B. Williams, Jr.

For example, when the district marker is in condition to be operated in accordance 30 with the office code registered upon the registering mechanism, a connection is extended to the conductor 233 which extends as stated in parallel to the grid wires 234, 236 and 238. Through the operation of the 35 card 222, the grid wire 234 is connected to the marker wire 235; the grid wire 236 through the operation of card 224 is connected to the marker wire 237; and the grid wire 238 through the operation of cards 225 40 and 226 is connected to the marker wires 239 and 240. Similarly, when the line marker is in readiness to be operated in accordance with the numerical registrations of the 45 registering mechanism, the wire 241 is connected in parallel to the grid wires 242, 264, 245, 248 and 250. The grid wire 242 through the operation of card 227 is then connected to marker wire 243. Grid wire 244, in this 50 instance, is without connection to any marker wire of the group 244, since the hundreds digit was zero. The grid wire 245 is connected through the operation of cards 228 and 229 to marker wires 246 and 247; grid wire 248, through the operation 55 of card 230 is connected to the marker wire 249 and grid wire 250 through the operation of cards 231 and 232 is connected to the 60 marker wires 251 and 252.

If the desired connection is to be established 60 through a manual operator's position and the registering mechanism is, therefore, connected to the call indicator impulser of the sender the second and third grid wires 65 associated with each group of registering cards, which are respectively connected to

battery through a high resistance element 255 and a low resistance element 254, are connected selectively with marker wires extending to the call indicator impulser. For example, marker wire 256 of the group 253 70 is connected through the lower contact of card 222 to grid wire 265; marker wire 258 is connected through the second contact of card 224 to grid wire 266; marker wire 260 is connected through the second contact of card 225 to grid wire 261 and marker wire 263 is connected through the lower contact of card 226 to grid wire 262, and so on for the remaining groups of registering elements. 80

After the markers have been set circuits may be closed in the manner fully set forth in the aforesaid patent to S. B. Williams, Jr. for determining the selective operation of the switches such as switch 106. For example, the trunks 142, 143, 144, etc. which may represent different numerical groups may be controlled by magnets or relays 108, 109, 110, etc. under the control of the markers. When the connection has been completed up to such a point that the recording and registering mechanism is no longer required, the circuit of relay 111 is maintained opened permitting the release of relay 115, which at its left contact removes ground from the conductor 145, releasing all operated horizontal magnets 206—220 and the operated transfer relays 207—221. Upon the release of magnets 206—220, the horizontal bars of the registering mechanism are released, permitting the operated registering cards to restore to normal condition and open the circuits which have been established. All apparatus of the recording and registering mechanism is now in normal condition. From this point, the connection from the calling line is established and released in the well-known manner. 100 105

What is claimed is:

1. In a switching system, a plurality of 110 switching devices coordinately arranged in rows, a plurality of selecting bars individual respectively to rows of devices in one co-ordinate direction, a plurality of operating bars individual respectively to rows of devices in the other co-ordinate direction, means for selectively operating said selecting bars, and means for operating one or more of the devices in a row associated with an operating bar through the conjoint operation of one or more of said selecting bars and one of said operating bars. 115

2. In a switching system, a plurality of 120 switching devices coordinately arranged in rows, a plurality of selecting bars individual respectively to rows of devices in one co-ordinate direction, a plurality of operating bars individual respectively to rows of devices in the other co-ordinate direction, means for selectively operating said select- 125 130

ing bars, and means for successively operating one or more of the devices in each of the rows of the last named coordinate direction through the repeated and conjoint 5 operation of one or more of said selecting bars with successive ones of said operating bars.

3. In a switching system, a plurality of switching devices coordinately arranged in 10 rows, a plurality of selecting bars individual respectively to rows of devices in one coordinate direction, a plurality of operating bars individual respectively to rows of devices in the other coordinate direction, 15 and means for successively operating varying combinations of the devices in each of the rows of the last named coordinate direction through the repeated simultaneous 20 operation of varying combinations of said switching bars with successive ones of said operating bars.

4. In a telephone system in which connections are established in accordance with the designations of desired connections under the control of a central office sender, a 25 unitary registering mechanism individual to the sender for registering all digits of complete call designations, comprising a plurality of groups of registering elements for registering respectively the several digits of call 30 designations and means less in number than the numerical value of the largest digit to be registered for selecting elements of any group.

35 5. In a telephone system in which connections are established in accordance with the designations of desired connections under the control of a central office sender, a unitary registering mechanism individual 40 to the sender for registering all digits of complete call designations, comprising a plurality of groups of registering elements for registering respectively the several digits of call 45 designations, means less in number than the numerical value of the largest digit to be registered for selecting elements of any group, and means individual respectively to the several groups of elements and successively operating in conjunction with 50 said first means for operating the selected elements of said groups.

6. In a telephone system in which connections are established in accordance with the designations of desired connections under the control of a central office sender, a 55 unitary registering mechanism individual to the sender for registering all digits of complete call designations, comprising a plurality of groups of registering elements 60 for registering respectively the several digits of call designations, means repeatedly operated in response to successive digits to be registered for successively selecting

elements of said several groups, and means individual respectively to the several groups 65 of elements responsive to successive digit series and operating successively in conjunction with said first means for operating selected elements of said groups.

7. In a telephone system in which connections are established in accordance with the designations of desired connections under the control of a central office sender, a unitary registering mechanism individual to the sender for registering all digits of 70 complete call designations, comprising a plurality of groups of registering elements for registering respectively the several digits of call 75 designations, and means less in number than the numerical value of the largest digit to be registered operating singly or in combination for selecting one or more elements of any group.

8. In a telephone system in which connections are established in accordance with the designations of desired connections under the control of a central office sender, a unitary registering mechanism individual to the sender for registering all digits of complete call designations, comprising a plurality of groups of registering elements for registering respectively the several digits of call 80 designations, means less in number than the numerical value of the largest digit to be registered operating singly or in combination for selecting one or more elements of any group, and means individual respectively to the several groups of elements and successively operating in conjunction with said 85 first means for operating the selected elements of said groups.

9. In a telephone system in which connections are established in accordance with the designations of desired connections under the control of a central office sender, a unitary registering mechanism for the sender for registering all digits of complete call 90 designations, comprising a plurality of groups of registering elements coordinately arranged in rows, a plurality of selecting 95 bars individual respectively to rows of elements in one coordinate direction, a plurality of operating bars individual respectively to rows of elements in the other coordinate direction, means for operating said 100 selecting bars singly or in combination in response to each digital series of impulses to be registered, means for successively operating said operating bars in response to successive series of impulses, and means jointly controlled by said selecting and operating bars for operating said registering elements.

In witness whereof, I hereunto subscribe my name this 16th day of October A. D., 1923.

OWEN C. FROM.
